UNITED STATES PATENT OFFICE.

EUGENE PEARL, OF PASSAIC, NEW JERSEY.

SHOE-SUPPORT.

1,173,733.

Specification of Letters Patent.

Patented Feb. 29, 1916.

Application filed October 25, 1915. Serial No. 57,749.

To all whom it may concern:

Be it known that I, EUGENE PEARL, a citizen of the United States, and a resident of Passaic, in the county of Passaic and State 5 of New Jersey, have invented new and useful Improvements in Shoe-Supports, of which the following is a specification.

This invention relates to improvements in supports or stands for shoes while being 10 cleaned and polished and the principal object is to provide a rest upon which the feet, incased in shoes, may be placed, the stand having devices engageable with the shoe soles and heels whereby they are held firmly 15 against lateral or other displacement when desired, or the engaging devices retracted, so as to cause no entanglement or obstruction when not in use.

Another object is to provide such stands 20 in forms of neat and attractive appearance, at a moderate manufacturing cost and which may be utilized as permanent advertising mediums.

These and other allied objects are attained 25 by the novel construction and combination of parts hereafter described and shown in the accompanying drawings, forming a material part of this specification, and in which:

30 Figure 1 is a perspective view of a support made in accordance with the preferred form of the invention, the shoe engaging means being extended as in use. Fig. 2 is a similar view, showing the upper part of 35 the support, the engaging means being retracted. Fig. 3 is a longitudinal sectional view, taken on line 3—3 of Fig. 2. Fig. 4 is a bottom plan and sectional view of the shoe plate. Fig. 5 is a fragmental view at 40 the heel, showing the operating mechanism. Fig. 6 is a sectional view taken on line 6—6 of Fig. 3. Fig. 7 is a bottom plan view of a stand showing a modified form of construction. Fig. 8 is a longitudinal sectional 45 view, taken on line 8—8 of Fig. 7. Fig. 9 is a bottom plan view, showing another modification in construction. Fig. 10 is a sectional view of the same, taken on line 10—10 of Fig. 9, and Fig. 11 is a perspective view showing a detail.

In the preferred embodiment, best shown in Fig. 1, a plate 15 of any desired outline, is provided with holes to receive the screws 16 by means of which the stand may be secured to its foundation: from the plate rises 50 a standard 17, branched as at 18 and 19,

respectively at the front and rear, and extending up to the shoe plate 20, the latter being preferably curved upward at the front 21, to receive the shoe sole, and having a 60 depressed heel receiving portion 22 at the back.

These stands are preferably formed in one piece, by common methods of casting, from brass or iron as may be desired and 65 finished with such ornamentation as fancy may suggest; the space between the branches 18 and 19 may obviously be utilized for advertising matter of a permanent nature.

In the front portion of the plate 20 is a 70 cored transverse slot 24 extending entirely through the plate and fitted slidably in it is a double spur 25, of sheet metal, as steel, with a straight flat back 26, the sides being parallel and formed with a plurality of 75 sharp teeth or serrations 27 in their edges adapted to engage with a shoe sole. The spur is held downward so that the teeth 27 are slightly below the surface of the plate 20 by means of a flat spring 28 disposed 80 lengthwise between the sides of the spur, the ends of the spring extending past the ends of the slot 24 and being partially embedded in the plate at its under side so as to remain in position. A cam 30 pivotally 85 mounted on the screw 31, set in the branch 18, is provided with a handle 32 and so arranged that when the handle is swung in a direction opposite to that shown in Fig. 6, the cam will press against the back 26 of 90 the spur, causing the teeth to extend above the surface of the plate 20 and engage with the shoe sole placed thereon. A narrow slot 35 is formed in the offset portion of the plate above the heel rest 22 and movable in 95 it is another spur 36 having an exterior flange 37 against which presses a flat spring 38 tending to hold the spur outwardly and against the cam 40, pivoted by the screw 39 to the plate 20, and provided with the 100 handle 41. The operation of the heel spur will be clearly understood from an inspection of Figs. 4 and 5.

In Figs. 7 and 8 a modified form of stand is shown in which a single handle or lever 105 movement only is required to project or retract the spurs at both the sole and heel. In this form the front branch 18 of the standard is fitted with a coarse pitched screw or one of multiple thread 45 to the outer end of 110 which is rigidly attached the wide faced cam 46, having the operating handle 47 and

actuating the spur 25 as before described; in place of the flat spring, a pair of coiled springs 49 set in the shoe plate press against the back of the spur which is extended in 5 length as at 48, beyond the ends of the slot in which the spur operates. A rod 52 extends from the screw 45 toward the rear of the plate and is held to it by means of the clip 53, the enlarged end 54 abutting against 10 the rear spur 55 in such manner as to force it out when the rod is turned clockwise by means of the cam handle 47 while the springs 56 keep it normally retracted.

A further modification is shown in Figs. 15 9 to 11, in which pivoted cams are dispensed with, a manually operated sliding cam or wedge taking their place at the front. In this style the front spur is normally held down by the spring device before described 20 and raised by pushing the handle 60 attached to the cam 61 so that as it advances the spur will be elevated. A rod 63 passes through the branch 18 where it is provided with a collar 64 limiting its outward movement, the rod having at its outer end a 25 second cam 65 slideable in the branch 19 and operating a vertical movable spur 66 adapted to engage the heel; at the same time a spur 67 is advanced engaging the front of the heel 30 as in the previously described constructions.

From the foregoing it will be seen that means are provided to support a shoe and to engage with the sole and heel in such manner as to hold it firmly during the temporary 35 period required; also that when not in actual use the spurs may be retracted so as not to catch or interfere with the clothing of persons using the same, and it will be further evident that many modifications and variations may be made embodying the application 40 of the principal elements in the appended claims; it is not therefore desired to be limited to the exact constructions shown.

Having thus described my invention and 45 ascertained the manner of its construction and use what I claim as new and desire to secure by Letters Patent is:—

1. In a foot support, the combination with 50 a fixed stand and a plate carried thereby, of a spur vertically operable in said plate, means for positively raising the spur above the surface of said plate, and means for normally maintaining said spur in a retracted position below the surface of the plate.

55 2. In a foot support, the combination with a fixed stand and a plate carried thereby having a depressed heel portion, of a spur slideable longitudinally in said plate adapted

to project horizontally over the surface of the heel portion, means for sliding said spur outwardly, said means being pivoted vertically to said plate and operable laterally thereof, and means for retracting said spur, said means operating in a plane parallel with and closely adjacent to said plate. 60 65

3. In a foot support, the combination with a fixed stand and a plate carried thereby having a depressed heel portion, of a spur extensible above said plate adapted to engage with a shoe sole, means for projecting said spur, and means for retraction thereof, a spur movable parallel to and above said depressed portion, means for actuating said spur outwardly to engage with a heel and means for retracting said heel spur. 70 75

4. In a device of the class described, the combination with a rigid stand, a plate adapted to receive a shoe supported by said stand, a plurality of spurs arranged transversely in said plate, and vertically operable 80 therein, means for raising said spurs, said means also being capable of maintaining them in a raised position and a spring for retracting said spurs, operative upon the release of said raising means. 85

5. In a device of the class described, a stand, a plate having an upwardly curved front end and a rear portion of reduced height, said plate being suited to the sole and heel of a shoe, of a plurality of spurs 90 operable in the plate between the upper and lower portions thereof adapted to engage with a shoe heel, means for projecting said spurs outwardly and holding them extended, said means being operative in a plane parallel to said plate and a spring for retracting said spurs upon the release of said projecting means. 95

6. In a device of the class described, a stand, a plate having an upwardly curved 100 front end and a rear portion of reduced height, said plate being suited to the sole and heel of a shoe, of a plurality of spurs engageable through said plate with the sole of a shoe, a second spur engageable with the heel of the shoe transversely to the plane of said plate, other spurs engageable with the bottom of the shoe heel, means for operating said spurs whereby they are advanced and held in an advanced position and means for 110 retracting said spurs upon release of said advancing means.

In testimony whereof I have signed my name to this specification.

EUGENE PEARL.
